UNITED STATES PATENT OFFICE

151,722

DESIGN FOR A DISPENSING DEVICE FOR DOG BISCUITS OR THE LIKE

Frederick E. Welsh, Springwater, N. Y.

Application September 7, 1946, Serial No. 133,162

Term of patent 14 years

(Cl. D52—2)

To all whom it may concern:

Be it known that I, Frederick E. Welsh, a citizen of the United States, residing at Springwater, Livingston County, State of New York, have invented a new, original, and ornamental Design for a Dispensing Device for Dog Biscuits or the like, of which the following is a specification, reference being had to the accompanying drawings, forming a part thereof.

In said drawings:

Fig. 1 is a perspective view of a dispensing device for dog biscuits or the like, showing my design.

Fig. 2 is a plan view thereof, on a reduced scale.

Fig. 3 is a rear elevational view thereof on a reduced scale.

Fig. 4 is a side elevational view thereof on a reduced scale.

I claim:

The ornamental design for a dispensing device for dog biscuits or the like, substantially as shown.

FREDERICK E. WELSH.
